Patented Nov. 22, 1927.

UNITED STATES PATENT OFFICE.

JAMES C. WILLIAMSON, OF CORDELE, GEORGIA, ASSIGNOR TO W. A. THOMPSON, OF CORDELE, GEORGIA.

FIREPLACE STOVE.

Application filed April 23, 1924. Serial No. 708,476.

This invention relates to fireplace stoves and aims to provide novel means for utilizing the heat radiating from the rear wall of the fireplace for heating the room in which the fireplace stove is positioned.

Another important object of the invention is to provide a device of this character which will cause the air in the room to circulate, insuring ventilation.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a front elevational view of a fireplace constructed in accordance with the invention.

Figure 2 is a plan view thereof.

Figure 3 is a vertical sectional view through the fireplace.

Referring to the drawings in detail, the fireplace stove includes spaced walls 5 and 6 respectively, the walls being irregularly formed as clearly illustrated by Figure 3 of the drawings to increase the heating space of the passageway and insure a thorough heating of the air as it passes therethrough.

The wall 5 is formed with external horizontal ribs 5', the wall 6 being undulated and defining horizontal grooves 6' into which the ribs project.

Formed in the wall 5 are bores 7 which may be provided with couplings at their ends, whereby suitable pipes leading to radiators may be attached, thereby utilizing the heat radiating from the rear wall and which usually passes upwardly through the chimney, for heating the water in the bores where it may be lead to the radiators in an adjoining room for heating purposes.

As shown, the bottom wall 9 of the fireplace stove is spaced from the wall 10 thereof, providing a passageway at the bottom

of the fireplace stove, which communicates with the passageway between the walls 5 and 6, there being provided a register 11 in the front wall of the fireplace stove to allow air to pass into the passageway between the walls 9 and 10.

In order that the ashes from the fireplace stove may be readily removed, a closure 12 is provided for normally closing the chute 13 formed in the bottom of the fireplace stove, it being understood that the closure 12 may be removed, permitting the ashes to fall from the fireplace stove.

As clearly shown by Figure 3 of the drawings, a pipe 14 establishes communication with the space between walls 5 and 6, and the interior of an adjacent room, the pipe providing means to allow air to be drawn into the passageway ventilating the adjacent room.

Located at the upper end of the passageway provided between the walls 5 and 6 is a register 15 which may be operated to allow heated air that passes through the passageway to enter the room at a point above the fireplace stove.

A damper 17 is provided in the pipe 16 for controlling the passage of heat through the pipe.

The forward portion of the fireplace stove may be open, but in the present showing, doors 18 and 19 are illustrated as having hinged connection with the frame or body portion of the fireplace stove, the doors being formed with suitable openings controlled by slides, whereby air passing through the openings may be controlled.

From the foregoing it will be obvious that due to the construction as shown and described, it is possible to position a fireplace stove constructed in accordance with the invention, eliminating the necessity of making alterations in the usual built-in fireplace stove now in common use.

I claim:

A fireplace stove to be positioned in a fireplace, said stove including an inner wall and an outer wall spaced from the inner wall, said inner wall having a lower horizontal

portion spaced from the bottom of the outer wall, the rear wall having a plurality of curved outwardly disposed horizontal ribs, said outer wall being undulated defining horizontal grooves into which certain of the ribs project, thereby providing an irregular passageway having a substantially wide

lower end portion, and said passageway having inlet and outlet openings.

In testimony that I claim the foregoing ¹⁰ as my own, I have hereto affixed my signature.

JAMES C. WILLIAMSON.
